(57) **CLAIM**

The ornamental design for a stackable washer tossing game, as shown and described.

DESCRIPTION

FIG. 1 is a perspective view of a stackable washer tossing game showing our new design;

FIG. 2 is a top plan view thereof;

FIG. 3 is a bottom plan view thereof;

FIG. 4 is a right side elevational view thereof; the left side elevational view being a mirror image thereof; and,

FIG. 5 is a perspective view thereof; with the game shown in a stackable position; the broken line showing of the upper game unit is for illustrative purpose only and forms no part of the claimed design.
